UNITED STATES PATENT OFFICE.

WILLIAM HERBERT McCANDLISH, OF WARE, ENGLAND, ASSIGNOR OF ONE-THIRD TO SABULITE (GREAT BRITAIN) LIMITED, OF LONDON, ENGLAND, A BRITISH COMPANY, AND ONE-THIRD TO JOHN BELLINGHAM, OF ST. CLEMENTS, JERSEY, CHANNEL ISLANDS, ENGLAND.

MACHINE FOR MOLDING AND PRESSING CONCRETE AND SIMILAR MATERIAL INTO BLOCK FORM.

Application filed June 1, 1922. Serial No. 565,217.

To all whom it may concern:

Be it known that I, WILLIAM HERBERT McCANDLISH, a subject of the King of Great Britain, of Barwick Ford, High Cross, 5 Ware, in the county of Herts, England, have invented certain new and useful Improvements in or Relating to Machines for Molding and Pressing Concrete and Similar Material into Block Form, of which the 10 following is a specification.

This invention relates to machines for molding and pressing concrete and similar material into block form and more particularly has reference to downwardly discharging mould boxes for use in connection therewith of the kind adapted to be inverted for filling or charging and having a bottom pallet adapted to discharge the pressed article or block onto a supporting table and 15 being provided with movable side walls pivotally mounted within a casing and with actuating means adapted to displace the side walls outwards and to withdraw the cores usually employed in connection therewith from the pressed material so as to enable the finished article or block to be discharged onto the said supporting table.

In accordance with the invention I provide a mould box in which the four walls 20 or doors of the mould are adapted to be opened and closed by the rotation of a shaft or spindle extending transversely through the mold box and the mold box casing. The said spindle or shaft is provided at its respective ends with oppositely screw threaded portions each engaging with an internally screw threaded nut each of which nuts carries two pins engaging in slots in a pair of pivotally mounted arms, each pair of 25 arms being secured to a bar of T or other suitable section adapted to be moved by the aforesaid arms to effect the withdrawal or insertion of the core pins when these are used and also to effect the opening and closing 30 of the side walls or doors of the mold box. In one embodiment of the invention the end doors of the mold box are also held in closed position by extensions of the said T or other shaped bars, spring means being 35 provided to open said doors when released on withdrawal of the said bars, while in another constructional form of the invention the aforesaid bars are used to operate 40

the side walls only, the end doors being opened by means of a pair of eccentrics 55 mounted on the ends of the operating spindle, the said eccentrics being connected with links, the outer ends of which are connected with eccentrics mounted on shafts or spindles passing through angle bars secured to the said end doors.

In order that the said invention may be clearly understood and readily carried into effect, the same will now be described more fully with reference to the accompanying drawings in which:

Figure 1 is a side elevation partly in section of one embodiment of the invention.

Figure 2 is a part sectional plan thereof.

Figure 3 is a section taken at right angles 70 to Figure 2.

Figure 4 is a section showing the closing mechanism of the end doors.

Figure 5 is a transverse section showing the side doors of the mold opened and the 75 core pins in their withdrawn position.

Figure 6 is a fragmentary section showing one end of the mould box with the side doors being closed and the core pins in their withdrawn position.

Figure 7 is a view partly in section of one side of a modified form of mold box.

Figure 8 is a sectional plan of the same, and

Figure 9 is a fragmentary section at right 85 angles to Figure 8.

Referring first to Figures 1 to 6 the mold box proper is located within a casing comprising side walls 1^a and end walls 1^b bolted together. The four walls of the mold box 90 are adapted to be opened and closed by the actuation of a spindle 42 passing through the mold box and which is provided with a squared end 43 for engagement by a suitable operating tool or handle said squared 95 end extending through an opening in the wall 1^a of the mold box casing. At or near each extremity the spindle 42 is screw threaded, at one end with a right hand thread and at the other with a left hand thread, an interiorly threaded nut 44 being arranged on each such end. Each nut 44 carries two pins 45 engaging in slots 46 in arms 47 which are pivoted at 48 to the mold box casing, said arms being connected 100 at their lower ends to a bar 49 of T or other

suitable section adapted to engage a portion 2^c of the side walls 2^b of the mold box which side wall is pivoted at 48^a to the mold box casing. One edge of this T-bar 49 is 5 adapted to fit between collars 50 formed on or carried by the core pins 38. In this manner when the spindle 42 is rotated the nuts move along the threaded portion causing the swinging of the arms 47 and the opening or 10 closing of the side doors 2^b as well as the insertion or withdrawal of the core pins 38. In order to prevent the nuts 44 rotating, pins 51 engaging in grooves in said nuts 44 are provided, the said pins 51 being 15 screwed into orifices in the wall 1^a of the mold box casing.

A leaf or other spring 52 (Figure 2) is arranged in front of the T-bar 49 to hold the door in closed position until after the pins 20 38 are withdrawn from the mould whereupon the T-bar causes the opening of the mould box as above described. For controlling the opening and closing of the end doors 2^d the T-bars are bent to extend around the 25 ends of the mould box as best seen in Figure 4 in which the bent end of the bar 49 is shown as provided with a shoe or cam surface 53 adapted to ride over a ball 54 located in a recess in a lug 55 secured to or integral 30 with the door 2^d. The doors 2^d are normally held in open position by springs (not shown). When the T-bar 49 is moved consequential upon rotation of the spindle 42 in a direction to close the door the cam surface 35 53 moving over the ball 54 depresses the lug causing the door 2^d to swing about its pivot and close against the action of its spring, the cam surface 53 being formed with an inclined portion 53^a adapted to coact with 40 the ball 54 to hold the door in closed position.

A modification of the mold box is illustrated in Figures 7 to 9. In this form the arms 47 are secured at their lower ends to an angle bar 49 carrying a bar 56 engaging in a slot or groove in the core pins 38. This bar 56 is attached to the angle bar 49 by studs or pins 56^a passing through slots 56^b in the bar 56 so that the bar 56 can be moved 50 against the action of a spring (not shown) to bring the cut away portions 56^c of the bar 56 into register with the core pins 38 thus permitting the latter to be withdrawn and fitted into any of the other orifices 57 provided 55 in the door 2^b and the boss 57^a formed thereon (see Figure 7). The side doors are thus operated in this form of the invention in substantially the same way as described above with reference to Figures 1 to 6. A 60 spiral spring 52' is in this form used instead of the leaf spring 52 however. For controlling the end doors however in this embodiment a pair of eccentrics 58, 59 are mounted upon the spindle 42 said eccentrics being 65 connected respectively by links 60, 61 with

the shafts or spindles 62 which, to provide for adjustment, are formed with eccentric end portions, the said spindles 62 being secured in any suitable manner to extensions 63 of the end doors 2^d as shown in Figure 8. 70

The mould is intended to be mounted so as to be inverted from the position shown in Figure 1 for charging, only sufficient material being filled as will extend to below the spindle 42 when the mould is in the position shown in the drawings, a suitable top plate or pallet 70, as shown in dotted lines in Figure 5 is used; a bottom pallet 65 is also intended for use being held in position by the hooks 64, (Figure 9).

It will be understood that I do not desire to confine myself to the exact construction and arrangement described above as many modifications may be made therein coming within the spirit of the invention.

What I claim and desire to secure by Letters Patent of the United States is:—

1. A mould box of the kind referred to for molding concrete and similar material in block form in which the four walls or doors of the mould are opened and closed by rotation of a shaft or spindle extending transversely through the mould box.

2. A mould box in accordance with claim 1 in which the said spindle or shaft is provided at its respective ends with oppositely screw threaded portions each engaging with an internally screw threaded nut each of which nuts carries two pins engaging in slots in a pair of pivotally mounted arms, the free ends of each pair of said arms being secured to a bar of T or other suitable section adapted to be moved by the aforesaid arms to effect withdrawal or insertion of the core pins and also to effect the opening and closing of the side walls or doors of the mould box.

3. A mould box in accordance with claim 2 in which the end doors of the mould box are held in closed position by extensions of the said T or other shaped bars, a ball mounted in a recess in each of said doors, and a cam surface adapted to coact with said ball to maintain the door in the closed position.

4. A mould box comprising movable side and end walls, a rotatable spindle extending through the box, and means connected with the spindle for moving the side and end walls simultaneously.

5. An invertible mould box for molding concrete and similar material into block form having movable walls and a spindle extending through the box for moving the walls, the box being filled with concrete and similar material to one side of the spindle.

6. A mould box for molding material comprising movable walls and a spindle extending through the box and operably connected with the said walls, the mold box being constructed for being filled with material on one side of the spindle.

7. An invertible mold box embodying movable side and end walls, a transverse spindle extending through the box and side walls and means operably connected with the spindle for moving the side and end walls, the mold being constructed to be filled on one side of the spindle when inverted. 5
8. A mold box comprising movable side and end walls, a spindle extending through the box and side walls, core pins, and means operably connected with the spindle and core pins for moving the side walls and for moving the core pins relatively to the side walls. 10
9. A mold box comprising movable side and end walls, a spindle extending through the box and side walls, core pins movable relatively to the side walls, means operably connected with the spindle and core pins and springs disposed between the side walls and 15 a part of the said means.
10. A mold box comprising a casing, movable side and end walls, a spindle extending through the box and side walls, arms pivoted to the casing, means operably connected to the spindle and engaging said arms, and bars connected to said arms for moving the 20 said side walls.
11. A mold box comprising a casing, movable side and end walls, a spindle extending through the box and side walls, arms pivoted to the casing, means operably connected to the spindle and engaging said arms, bars connected to the said arms, and springs disposed between the bars and side walls. 25
- 35 12. A mold box comprising a casing, movable side and end walls, a spindle extending through the box and side walls, arms pivoted to the casing, means operably connected to the spindle and engaging said arms, core pins movable relatively to the side walls, bars attached to said arms and engaging the said core pins, and springs disposed between the said arms and side walls. 40
- 45 13. A mold box comprising a casing, movable side and end walls, a spindle provided with right and left hand screw threads and extending through the box and side walls, arms pivoted to the casing, nuts on the said spindle engaging the right and left hand screw threads and connected with the said arms, and bars on the said arms for moving the side walls. 50
- 55 14. A mold box comprising a casing, movable side and end walls, a spindle provided with right and left hand screw threads and extending through the box and side walls, arms pivoted to the casing, nuts on the said 60
- spindle engaging the right and left hand screw threads and connected with the said arms, bars provided with cam shaped ends attached to the said arms, and lugs on the end walls for the engagement of the cam shaped ends. 65
15. A mold box comprising a casing, movable side and end walls, a spindle provided with right and left hand screw threads and extending through the box and side walls, arms pivoted to the casing, nuts on the said spindle engaging the right and left hand screw threads and connected with the said 70
- arms, core pins with collars, bars engaging the said collars and provided with cam shaped ends attached to the said arms, lugs fitted with balls attached to the end walls and engaged by the cam shaped ends, and 75 springs between the bars and the side walls.
16. A mold box for molding concrete and similar material in block form comprising movable side and end walls, a spindle extending across the box and through the side 80 walls and provided at its respective ends with oppositely screw threaded portions, internally screw threaded nuts provided with pins and mounted on the threaded portions of the spindle, a mold box casing, arms 85 having free ends and pivotally mounted on the casing and formed with slots with which the said pins engage, bars secured to the free ends of the said arms, core pins engaged by the said bars, and means for rotating the 90 spindle and thereby moving the arms and bars through the said nuts. 95
17. A mold box for molding concrete and similar material in block form comprising movable side and end walls, a spindle extending across the box and through the side 100 walls and provided at its respective ends with oppositely screw threaded portions, internally screw threaded nuts provided with pins and mounted on the threaded portions of the spindle, a mold box casing, arms having free ends pivotally mounted on the casing and formed with slots with which the said pins engage, bars provided with cam shaped ends and secured to the free ends of the said arms, core pins engaged by the said 105 bars, lugs on the end walls engaged by the cam shaped ends of the bars, springs between the bars and the side walls, and means for rotating the spindle and moving the arms 110 and bars for operating the side and end walls.

WILLIAM HERBERT McCANDLISH.
